EXTENSION TABLE

Joseph Cooper, New York, N. Y.

Application April 2, 1934, Serial No. 718,544

3 Claims. (Cl. 311—41)

The object of the present invention is to provide an extension table comprising a plurality of top members adapted to lie one above the other when the table is closed and which are so supported as to have relative outward movements, without mutual interference, in order that the table may be extended with the top members, when two are employed, abutting in a line centrally of the supporting frame.

10 The invention relates particularly to the means by which the movement of the top members is controlled.

The invention will be described with reference to the accompanying drawings, in which

15 Fig. 1 is a plan view of the table in closed position, indicating, in dotted lines, certain elements of the support and controlling means for the top members.

Fig. 2 is a transverse sectional elevation on the line 2—2, Fig. 1.

20 Fig. 3 is a longitudinal sectional elevation on the line 3—3, Fig. 7.

Fig. 4 is a fragmentary horizontal section on the line 4—4, Fig. 3.

25 Fig. 5 is a vertical section on the line 5—5, Fig. 10.

Fig. 6 is a perspective view, partly in section, and partly broken away, taken at the corner of a table constructed in accordance with the invention.

30 Fig. 7 is a sectional elevation on the line 1—1, Fig. 1, showing the table in closed position.

Fig. 8 is a view similar to Fig. 7, showing the upper top member extended and the normally under top member partially extended.

35 Fig. 9 is a view similar to Fig. 7 showing the normally under top member in fully extended position.

Fig. 10 is a view similar to Fig. 7 showing the normally under top member moved inwardly from its position in Fig. 9 to abutment with the upper top member in the same plane.

40 A characteristic of the present invention, is the provision of opposed guiding rails, abutting opposed edges of two top members and serving to support and guide an upper top member for movement outwardly when the table is to be extended, and inwardly when the table is to be contracted, in combination with means for supporting and controlling the normally under top member from a position underlying the upper top member to a position in the same plane thereof.

45 In the drawings, Fig. 4, I have shown a customary form of supporting frame 1 to which are applied the usual legs 2. The opposed guide rails

are indicated at 3, and they are of a height equal to the combined height of the upper and normally under top members plus the distance they are separated when the normally under top member is in retracted position. This degree of separation may be .25" or even less, it only being required that the top members may be sufficiently spaced so that the movement of the normally under top member to open position and its return may be effected without friction. It will also be understood that all or part of the lower face of the upper top member may be covered with felt to prevent any marring of the normally under top member in such relative movement.

50 In the present embodiment, the rails 3 are held projected outwardly from the frame 1 by means of opposed cam plates 4 shown in plan, Fig. 4, these plates being secured to frame 1 by means of screws 5 and projecting laterally of their respective frame supports, the lateral projections being apertured as at 6 to receive screws by means of which the rails 3 may be secured. Each cam plate is formed with a depressed cam section 4x for a purpose hereinafter to be explained.

55 Each side rail 3 is formed with a longitudinally extending horizontal channel indicated at 3x to receive supporting lugs 1x carried by the upper top member 1 as shown more particularly in Figs. 4 and 6. When the top member 1 lies in the position of Fig. 7, that is to say, retracted, one of said lugs 1x abuts a stop pin 8, Fig. 4, and when top member 1 is moved to open or projected position, one of said lugs engages a stop pin 9 at the opposite end of channel 3x.

60 As noted more particularly in Fig. 3, the lower top member 10 abuts rails 3 at opposite edges, and therefore is guided by said rails. When the lower top member is in retracted position, it rests upon the opposed cam plates 4, as shown more particularly in Fig. 3 in conjunction with Fig. 4. When, however, the normally under top member is moved outwardly, it reaches a point where it is elevated above the cam plates 4 and finds support through other means, although still guided by rails 3.

65 The means for supporting the lower top member include spaced cam bars fixed to said top member at the lower surface thereof, and shown more particularly in Figs. 7 to 10 inclusive, at 11. Cam bars 11 are wholly inactive when the normally under top member is retracted, but when said normally under top member is moved outwardly to the position of Fig. 8, the cam surface a of each of the two cam bars engages a contiguous vertical member of frame 1 and the

outward movement causes the lower top member to be elevated centrally thereof, requiring the inner end to drop, the depressed cam section $4x$ of each cam plate 4 coming into register with the inner end of said normally under top member at its instant of rise centrally thereof. Thus, in the outward movement of the normally under top member, it reaches a point where it is rocked on a horizontal axis substantially centrally thereof, the outer end being moved upwardly and the inner end downwardly, as shown in Fig. 8. In the continued movement of the normally under top member, it reaches the position shown in Fig. 9, being stopped against further outward movement by the abutment of shoulder b of each cam bar 11 with the adjacent member of frame 1 . When the elements reach the position of Fig. 9, a horizontal section of an L-shaped supporting bracket 12 will lie in a line just above a strong supporting finger 13 . As shown in Fig. 3, two brackets 12 are carried by the lower top member and, as indicated in Fig. 1, one of the supporting fingers 13 is carried by each cam plate 4 . Thus, when the normally under top member 10 is moved inwardly from its position shown in Fig. 9 to that of Fig. 10, brackets 12 are moved over upon the upper surface of supporting fingers 13 , and the inner portion of said normally lower top member is firmly supported by said fingers, also the horizontal section of each bracket 12 engages the lower surface of the corresponding cam plate 4 , which prevents tilting of the said top member.

The operation of the table has been brought out in conjunction with the description of its construction. It will be understood that various modifications may be made in the construction of the embodiment without departing from the spirit of the invention; for example, in said embodiment side rails 3 are shown mounted directly on plates 4 which are, in turn, supported by vertically extending members of frame 1 . Said side rails may be supported by frame 1 through intermediaries other than the plates 4 . However, I prefer that the plates 4 be employed inasmuch as they afford convenient and inexpensive means for both supporting the side rails and as a major support for the top member 10 when the latter is in retracted position. Also, the cam-like depression $4x$ may readily be formed by a die when plates 4 are constructed of sheet metal.

Having described my invention, what I claim

and desire to secure by Letters Patent, is as follows:—

1. In an extension table, two top members superposed when in retracted position, a frame, side rails carried by said frame and abutting opposed edges of said top members, means intermediate the side rails and one top member permitting plane movement only thereof, cam bars carried by the other top member at its undersurface, a fixed abutment on said frame for engaging said cam bars whereby outward movement of said other top member will first tilt it and then move it upwardly to a horizontal position in the plane of said one top member, brackets carried by said other top member and substantially horizontal holding fingers carried by said frame and adapted to engage said brackets when the two top members are moved into edge abutment.

2. In an extension table, a top member, an extendible top member normally housed beneath said first top member, a frame, opposed side rails, plates carried by the frame, each plate projecting laterally from a frame member and supporting one of said side rails in offset relation with its adjacent frame member, means intermediate the side rails and the first named top member for supporting and permitting bodily movement of the latter in a single plane, and supporting and controlling means for said extendible top member and acting independently of the first named top member.

3. In an extension table, a top member, an extendible top member normally housed beneath said first top member, a frame, opposed side rails supported by the frame and lying contiguous to opposed side edges of said top members, means intermediate the side rails and the first named top member for supporting and permitting bodily movement of the latter in a single plane, supporting and controlling means for said extendible top member comprising two independent elements, one element being a supporting plate carried by the frame and formed with a cam-like depression to permit downward movement of an end of said extendible top member, and a second element being a cam bar carried by said extendible top member and co-acting with a fixed member of the frame to cause bodily elevation of said extendible top member when the same is moved in a direction away from the first named top member.

JOSEPH COOPER.
